UNITED STATES PATENT OFFICE.

JOSEPH W. VLAZNY, OF CICERO, ILLINOIS, ASSIGNOR TO UNIVERSAL GAUGE CORPORATION, A CORPORATION OF ILLINOIS.

RAZOR.

Application filed October 6, 1926. Serial No. 139,906.

My invention relates to certain new and useful improvements in razors and the objects of the invention are to provide a razor that is small, neat and compact for carrying purposes; to provide a razor that will be cheaper to manufacture than those now on the market and at the same time give equal shaving satisfaction; to provide a razor that will require less amount of high grade steel in its manufacture; to provide a razor in which the cutting edge or blade may be changed, honed or stropped with ease; to afford facilities for the proper gripping of a thin piece of steel blade without any holes or notches in the same and at the same time provide a gripping device or clip which will be out of the way for satisfactory shaving, honing and stropping; to secure the cutting blades sufficiently to cut light material such as hair or whiskers and at the same time afford an easy adjustment for the holder clip; to provide a bumper or stop for the cutting blade and clip; to provide a small razor with means for carrying the same on a chain; to provide a small razor that may be easily carried on a small chain around the neck by ladies; to provide a razor that may be used for cutting other soft material such as lead pencils, cloth, strings, corns, finger and toe nails without injuring the whole razor for shaving purposes; to provide a razor such that the very best quality of thin steel may be used for cutting light materials, at a very small cost; to provide a holder for the purpose of holding almost all makes of safety razor blades in a position so that the safety razor blades may be honed and stropped in the same manner as the old style straight blade razors.

The above objects I attain by the mechanism illustrated in the accompanying drawing in which:

Figure 1 is a perspective view showing the implement ready for use.

Figure 2 is a side elevation showing how the position of the blade and that of the handle may be varied or adjusted.

Figure 3 is a side elevation showing the position of the parts ready for honing or stropping.

Figure 4 is a view illustrating the manner of inserting the blade in the holder.

Figure 5 is a view illustrating the manner of placing the holding clip on the holder.

Figure 6 is an enlarged cross section on 55 the line 6—6 of Figure 1.

Figure 7 is a side elevation of the razor closed.

Figure 8 is a back view of the holder proper.

Figure 9 is a back view of the handle.

In the drawing, in which like numerals of reference indicate like parts in all the figures, 1—1 represent the side plates of the holder which are spaced apart for the shive or spacer member 2 to provide bifurcated ends 3 and 5, the former being the end to which the handle is attached and being apertured as at 4 to receive the snap fastener 13 of the carrying chain.

The bifurcated front end 5 of the holder is adapted to receive the wafer-like blade 12 and it is provided with beveled surfaces 6 adjacent the blade. The handle 9 is secured to the holder proper by means of the rivet 7 which, it will be observed, is offset from the center line or axis of the holder and the bifurcated portions of the handle are of less width than the width of the holder so as to expose the apertures 4 even 70 when the handle and holder are in longitudinal alignment, thus making it possible to align these two parts while the chain snap 75 13 is in the holes 4.

The side plates 1 and spacer member 2 are also secured by a rivet 8 located near the front end, this rivet 8 serving as a stop for the clip 11 and also has a stop for the handle member when it is folded over the cutting edge of the blade when the parts are 80 85 in the position shown in Figure 7, the handle having a blade protecting back 10 as shown.

The clip 11, it will be observed, is made of thin sheet metal of sufficient temper to 90 95 maintain its cross section and exert a gripping pressure on the bifurcated handle end to cause that end to grip the blade with retaining friction.

As will be seen from an inspection of Figure 2, the blade may be projected more or less from the handle and blades of various sizes may also be employed. Furthermore by reason of the resiliency of the bifurcated end adjacent to which the handle is pivoted and by reason of the bifurcations of the handle straddling the bifurcations of the holder, the holder bifurcations will exert an 100 105

outward pressure against the handle bifurcations to hold the handle with retaining friction in its various angular adjustments.

By my construction it will be seen that the 5 cutting blade may be adjusted, i. e. advanced or set in any position desired within the limits of the walls of the holder; so also the handle may be adjusted on its pivot to any of the desired angular positions with- 10 in the pivotal limits of its movement.

Attention is called to the fact that by my construction, a very narrow or thin holder is provided making it handier for use in most cases than the wide and clumsy razors of 15 this type now generally employed.

While my razor is especially adapted to hold wafer blades it is obvious that blades of other cross sections may be employed.

The clip 11 is so formed in cross section 20 that it can be easily slipped into position as indicated in Figure 5. This is done by making the back of the clip slightly wider than the thickness of the holder with the blade in place. With this arrangement the 25 edge or corner of the holder may be inserted in the end of the clip and will automatically spread the clip as the clip is pushed into position.

In manufacturing my device I prefer to 30 make the holder plates 1-1 of a stiff or hard material so as to maintain a sufficient rigidity for the purpose for which the razor is designed, while the handle may be made of a softer material so that it may be readily bent into the U-form.

By my arrangement also the blade may be 40 held in the holder during honing and stropping and by reason of the beveled edges 6 of the holder and the horseshoe shape of the clip in cross section the contact with the holder or with the razor strop is such as not to injure the holder or strop and as the razor is honed or stropped the entire outer 45 surface of the blade, the adjacent bevelled surfaces 6 of the holder and the sides of the clip are kept smooth and polished so that when the instrument is in use there is no danger of scratching the face while shaving for instance.

From the foregoing description, taken in 50 connection with the accompanying drawings, it is thought the complete construction and the advantages of my invention will be clear to those skilled in the art and I desire it understood that slight changes in the 55 details of construction may be made without departing from the spirit of the invention or the scope of the appended claims.

What I claim is:

60 1. An adjustable blade razor comprising a holder having a bifurcated end to receive a wafer-like blade between the bifurcations, and a holding clip fitted over one edge of the bifurcated end to apply retaining friction 65 pressures to the bifurcations of the holder

and thereby secure the blade, the other end of said holder being bifurcated and a handle pivoted adjacent to said other end and itself having bifurcated portions embracing the holder and having a channelled portion 70 adapted to close over the exposed portion of the razor blade to protect the same.

2. An adjustable blade razor comprising a holder having a bifurcated end to receive a wafer-like blade between the bifurcations, 75 and a holding clip fitted over one edge of the bifurcated end to apply retaining friction pressures to the bifurcations of the holder and thereby secure the blade, said holder having a stop for the razor blade and a handle to abut.

3. An adjustable blade razor comprising a holder having a bifurcated end to receive a wafer-like blade between the bifurcations, 80 and a holding clip fitted over one edge of the bifurcated end to apply retaining friction pressures to the bifurcations of the holder and thereby secure the blade, the other end of said holder being bifurcated and a handle pivoted adjacent to said other end 85 and itself having bifurcated portions embracing the holder and having a channelled portion adapted to close over the exposed portion of the razor to protect the same, said holder having a stop for the razor blade and 90 handle to abut.

4. A razor comprising a holder consisting of two elongated thin metal plates and a shive between the same to leave bifurcated ends, a bifurcated handle pivoted to the 100 holder adjacent one end, the bifurcations of the handle and holder when the handle is in the extended position cooperating to hold the handle in its various angular adjustments with retaining friction, and a wafer blade 105 held in the other bifurcated end of the holder, and means to hold the holder plates and the shive together as a unit.

5. A razor comprising a holder consisting of two elongated thin metal plates and a shive between the same to leave bifurcated ends, a bifurcated handle pivoted to the 110 holder adjacent one end, the bifurcations of the handle and holder when the handle is in the extended position cooperating to hold the handle in its various angular adjustments with retaining friction, a wafer blade located in the other bifurcated end of the holder, a U-clip held with gripping friction over said other bifurcated end to guard one 115 edge of the blade and applying gripping friction through the holder bifurcations to the blade to retain the same.

6. A razor comprising a holder consisting of two elongated thin metal plates and a shive between the same to leave bifurcated ends, a bifurcated handle pivoted to the 120 holder adjacent one end, the bifurcations of the handle and holder when the handle is in the extended position cooperating to hold the 125

handle in its various angular adjustments with retaining friction, a wafer blade located in the other bifurcated end of the holder, a U-clip held with gripping friction over said other bifurcated end to guard one edge of the blade and apply gripping friction through the holder bifurcations to the blade to retain the same, a rivet securing said holder plate and said shive together and serving as a stop for said clip and as a stop for said handle when said handle is folded over to protect the exposed edge of the blade.

7. A razor comprising a holder having provision at one end for retaining a wafer blade and having its other end bifurcated,

a bifurcated handle pivoted to the holder adjacent said bifurcated end, the bifurcations of the handle and holder when the handle is in the extended position cooperating to hold the handle in its various angular adjustments with retaining friction, said holder having chain snap-fastener receiving holes in its handle adjacent end and said handle having its bifurcated portion of reduced width and its pivotal connection located to one side of the axis of the holder, said holes being of a diameter whereby a portion thereof is exposed when handle and holder are in longitudinal alignment for the purposes specified.

JOSEPH W. VLAZNY.
